UNITED STATES PATENT OFFICE.

JOHN JACKSON, OF PORTSMOUTH, OHIO.

CANNON.

1,306,012.

Specification of Letters Patent. Patented June 10, 1919.

Application filed October 5, 1918. Serial No. 257,003.

To all whom it may concern:

Be it known that I, JOHN JACKSON, a citizen of the United States, residing at Portsmouth, in the county of Scioto and 5 State of Ohio, have invented certain new and useful Improvements in Cannons, of which the following is a specification.

This invention relates to ordnance of the type generally designated as heavy ordnance 10 and aims to provide a gun which is electrically and pneumatically operated and which is designed for field, coast guard and battleship service.

The main object of the invention is the 15 provision of a cannon which may be operated with ease and certainty and which has a long aim, the projectile being fired by successive explosions. The drawings illustrate a preferred embodiment of the invention, however, it is to be understood that in adapting the same to meet different conditions, various changes in the form, proportion and minor details of construction may be resorted to without departing from the 20 nature of the invention as claimed herein-after.

In the drawings:—

Figure 1 is a central longitudinal section of a cannon embodying the invention, the 30 muzzle portion of the barrel being broken away and the cylinder containing the breech block operating mechanism being in full.

Fig. 2 is a transverse section on the line 2—2 of Fig. 1 looking toward the muzzle of 35 the gun,

Fig. 3 is a central longitudinal section of the cylinder containing the breech block operating mechanism showing the parts on a larger scale,

Fig. 4 is a transverse section of the engine located within the piston forming a part of the breech block operating mechanism,

Fig. 5 is a cross section of the shaft and sleeve coöoperating with the cylinder and 45 piston of the breech block operating mechanism.

Corresponding and like parts are referred to in the following description and indicated in the several views of the drawings 50 by like reference characters.

The barrel 1 of the gun is mounted upon a carriage which comprises a frame 2, trailer 3, axle 4 and ground wheels 5. The barrel 1

is enlarged midway of its ends as indicated at 6 and its forward portion is rifled in the usual manner as indicated at 7. The breech of the barrel is formed with the usual thread sections 8 which are adapted to coact with corresponding thread sections 9 of the breech block 10. The elevation of the barrel is effected by means by a toothed segment 11 which is secured to the barrel in any substantial way. A worm 12 is in meshing relation with the teeth of the segment 11 and is carried by a shaft which is rotated by means of a motor 13 preferably of the electric type. Within the barrel 1 is located an electric contact 14 which forms one terminal of a firing circuit. A wire 15 from a battery 16 is electrically connected with the contact 14. A wire 17 from the other terminal of the battery 16 is grounded on the barrel. The battery 16 is preferably of the storage type. The projectile adapted to be fired from the gun is of the type containing within itself a firing charge and is initially fired by a charge placed in the breech of the gun. After the initial charge has been fired and during the movement of the projectile through the barrel, the second charge is fired by means of the firing circuit represented by the battery 16 and wires 15 and 17. The second charge is fired in the reinforced part 6 of the barrel, the latter being reinforced to withstand the force of the explosion.

A loading chamber 18 is disposed in the rear of the barrel 1 and is accessible by means of a side opening 19 indicated most clearly in Fig. 2. Elevating mechanism is disposed in the lower portion of the chamber 18 for lifting the projectile into position for delivery into the breech of the gun. The elevating mechanism comprises a plate 20 upon which the projectile is delivered and cylinders 21 with coöperating pistons 22. Fluid motive medium is supplied to the cylinders 21 below the pistons 22 by means of a pipe 23. A valve 24 in the length of the pipe 23 controls the supply of motive medium to the cylinders 21. The projectile is adapted to be supplied to the chamber 18 in any manner and is delivered upon the plate 20 after which the valve 24 is operated to supply the fluid medium to the cylinders 21 whereby the plate 20 is elevated and

lifts the projectile to a position in line with the barrel 1 into which it is pressed by the breech block 10 in the forward movement thereof as will be described more in detail 5 hereinafter.

A tank or reservoir 25 is for convenience mounted upon the trailer 3 and is adapted 10 to contain air under pressure, said tank being charged by means of an electrically operated air compressor 26 also mounted upon the trailer 3. The air for operating the elevating mechanism and the breech block actuating mechanism is derived from the tank 25. Rubber or flexible tubes 27 and 28 connect the tank 25 with the cylinders of the breech block and elevator mechanisms.

A cylinder 29 is located in the rear of the loading chamber in line with the barrel 1 and contains a piston 30. A rod 31 connects 20 the piston 30 with the breech block 10. The piston 30 is hollow and contains a pneumatically operated engine which comprises a crank case 32 and a plurality of cylinders 33. A crank shaft 34 mounted in the crank 25 case 32 projects at one end and has a pinion 35 secured to its projecting end and in mesh with a gear wheel 36 secured to the inner end of the rod 31. The purpose of the engine disposed within the piston 30 is to impart a 30 rotary movement to the breech block so as to effect a locking and an unlocking thereof in a manner well understood. A pipe 37 has its opposite ends connected with ports 38 and 39 at opposite ends of the cylinder 29. A 35 valve 40 in the length of the pipe 37 is adapted to control the supply of motive fluid to either end of the cylinder 29 whereby the piston 30 may be driven positively in each direction. The flexible tube 27 connects 40 with the pipe 37. Valves 41 and 42 are provided at opposite ends of the hollow piston 30 and open inwardly. An exhaust pipe 43 is connected with each of the cylinders 33 and is open in opposite ends of the piston 30 45 and is closed at its ends by means of valves 44 and 45. Two of the cylinders 33 are adapted to rotate the crank shaft 34 in one direction and the remaining two cylinders are adapted to rotate the crank shaft in the 50 opposite direction. Each of the cylinders 33 has an inlet 46 which is adapted to be closed by means of a valve 47 which latter is connected by means of a rod 48 with a cam 49 secured to or forming part of a 55 sleeve 50 which is slidably mounted on a rod 51 extending through the end of the cylinder 39 and the heads of the piston 30. The shaft 51 is journaled at its ends in the ends of the cylinder 29 and one end of the 60 shaft is threaded and provided with an operating crank 52 whereby the shaft 51 may be manually operated at will to admit the fluid motive medium into one or the other of the pairs of cylinders 33. The sleeve 50 65 is journaled in the heads of the piston 30

and is slidable on the shaft 51 and connected with said shaft so as to rotate therewith at any point in the travel of the piston. The cams 49 may be of any construction so long as they serve to effect an opening and a 70 closing of the valve 47 when the shaft 51 is rotated.

The operation of the gun is as follows:—

The projectile to be fired is supplied to the loading chamber 18 and is lifted by the 75 elevating mechanism into position to be pressed into the barrel 1. After the projectile has been elevated, the valve 40 is turned so as to admit the fluid motive medium into the cylinder 39 through the port 80 38 whereby the piston 30 is caused to travel forwardly and bring the breech block 10 into engagement with the projectile so as to force the same into the barrel of the gun. After the projectile has been properly positioned, the shaft 51 is turned by means of the crank 52 thereby opening the valve to 85 two of the cylinders 33 whereby the motive medium entering the piston through the valve 41 passes into two of the cylinders 33 90 and operates the pistons thereof to cause the crank shaft 34 to turn a distance so as to effect a locking of the breech block with the breech of the gun in a manner well understood. After the gun has been fired, the 95 shaft 51 is reversed so as to close the valves to the two cylinders 33 previously open and open the valves of the remaining two cylinders 33. The valve 40 is now reversed thereby admitting the motive medium into the 100 right hand end of the cylinder 29 through the port 39 and into the piston 30 through the valve control opening 42. The motive medium after entering the piston 30 passes into the two cylinders 33 last opened, thereby operating the pistons thereof and reversing the crank shaft 34 whereby the breech block is turned so as to cause the thread section 9 thereof to clear the thread section 8 of the breech. The breech block 110 being released is carried rearward by the motion of the piston 30 in the cylinder 29. The breech block is suitably guided into the breech of the gun and the latter is fired electrically by means of a firing element 53 carried by the breech block. After the initial charge is fired and the projectile has been started on its travel and after the same reaches a predetermined point in the length 115 of the barrel, a second charge preferably provided in the projectile is fired by an element thereon making electric connection with the contact 14 thereby insuring a great range being imparted to the projectile.

It is observed that the gun is designed 125 for the type of projectiles to be electrically fired and which contain a switch to coöperate with the element 53, the switch being closed at the proper instant by hand. As this feature is well understood and forms no 130

part of the present invention it has not been amplified, it being obvious that any firing mechanism may be employed.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claims.

Having thus described the invention, what I claim as new and desire to secure by Letters Patent, is:—

1. Breech block operating mechanism for a gun of the type specified, the same comprising a cylinder, a piston disposed to operate within the cylinder and having the breech block connected thereto, means for supplying a fluid motive medium to opposite ends of the cylinder, and means within the piston for imparting rotary movement to the breech block to effect the locking or an unlocking thereof.

2. Breech block operating mechanism of the character set forth comprising a cylinder adapted to have a fluid motive medium supplied to opposite ends thereof, a piston within the cylinder and having the breech block connected thereto, an engine within the piston, and connecting means between the shaft of said engine, and the breech block for imparting rotary movement to the latter to effect a locking or an unlocking thereof.

3. Breech block operating mechanism comprising a cylinder adapted to have a fluid motive medium supplied to opposite ends thereof, a hollow piston disposed within the cylinder and having valve controlled openings at opposite ends, a rod forming connecting means between the breech block and piston, and an engine disposed within the piston and operable by the same fluid motive medium supplied to the cylinder for driving the piston, and having connection with the said rod for imparting a rotary movement thereto and to the breech block whereby the latter is locked and released.

4. Breech block operating mechanism comprising a cylinder adapted to have a fluid motive medium supplied to opposite ends thereof, a hollow piston within the cylinder and having valve controlled openings in opposite ends to admit motive medium from the cylinder into the piston, a rod forming connecting means between the breech block and piston, an engine within the piston and operable by the fluid motive medium admitted into the piston from the cylinder, and means connecting the shaft of the said engine with the said rod for imparting rotary movement to the breech block.

5. Breech block operating mechanism comprising a cylinder, means for supplying motive medium to opposite ends of the cylinder, a hollow piston within the cylinder, a rod forming connecting means between the breech block and piston, an engine within the piston connected with the said rod for imparting a rotary movement thereto and to the breech block, and a valve mechanism within the piston and operable from without the cylinder whereby the supply of the motive medium to the said engine may be properly controlled.

6. In breech block operating mechanism, a cylinder adapted to have a fluid motive medium supplied thereto, a hollow piston within the cylinder and having a valve controlled opening, a rod forming connecting means between the breech block and piston, an engine within the piston and operable by the fluid medium supplied to the cylinder, a valve mechanism for controlling the supply of motive medium to the said engine, a shaft mounted in the cylinder, and a cam mechanism slidable on the said shaft and rotatable therewith and having connection with the said valve mechanism to admit of operating the same from a point without the cylinder.

In testimony whereof I affix my signature in presence of two witnesses.

JOHN JACKSON.
